UNITED STATES PATENT OFFICE.

NORMAN M. DYER, OF NEW YORK, N. Y.

TIE PRESS AND HOLDER.

1,371,879.

Specification of Letters Patent. Patented Mar. 15, 1921.

Application filed September 14, 1920. Serial No. 410,162.

To all whom it may concern:

Be it known that I, NORMAN M. DYER, a citizen of the United States, and a resident of the city of New York, borough of Manhattan, in the county and State of New York, have invented a new and Improved Tie Press and Holder, of which the following is a full, clear, and exact description.

This invention relates to improvements in tie presses and holders, an object of the invention being to provide a portable device which can be conveniently carried in the handbag of a traveler, and which will operate to hold or support any number of ties and exert sufficient pressure on the ties so as to smooth out the wrinkles.

A further object is to provide a tie holder which also operates as a press, which can be cheaply manufactured, which will occupy but relatively small space, and which will most efficiently perform the functions for which it is intended.

With these and other objects in view the invention consists in certain novel features of construction, and combinations and arrangements of parts as will be more fully hereinafter described and pointed out in the claim.

In the accompanying drawings—

Figure 1 is a perspective view illustrating my improved tie press and holder, showing the outside plates flared outwardly.

Fig. 2 is a similar view showing the parts in clamping position.

Fig. 3 is a view in section on the line 3—3 of Fig. 1, showing the side plates hinged outwardly.

My improved tie press and holder comprises in the main a pair of pressure plates 1, 1, which are curved longitudinally and hingedly connected at one end so that when the other ends of the pressure plates are secured together a necktie indicated by the reference numeral 2, can be held smoothly and under pressure between them, so as to press out the wrinkles of the tie.

In the preferred embodiment of this invention I provide between the plates 1, 1, a partition plate 3 and the pressure plates 1, 1, and the partition plate 3 are each provided with alined sleeves 4 for the reception of a hinge pin 5 to hingedly connect them together. This hinge pin 5 is preferably in the form of a wire having its ends twisted

or otherwise secured together, as shown at 6, 55 forming a supporting bail 7 for the tie holder, and this supporting bail may be suspended from a nail or other support 8 as clearly shown.

The pressure plates 1, 1, are both provided at their hinged ends with central recesses 9 which are of sufficient size to admit the two sections of an ordinary four-in-hand or bow tie, so that the tie can be placed in the holder with the two ends of the tie at opposite sides of the partition plate 3. It is, of course, to be understood that any number of ties may be so supported and simultaneously pressed or clamped.

While, of course, I may employ various 70 devices for securing the free ends of the plates together, I have illustrated for this purpose a wire bail 10 having its ends supported in suitable bearings 11 on one of the pressure plates 1, so that the intermediate portion of the bail can be positioned over the free end of the other pressure plate 1 and thereby hold all of the plates in parallelism.

As above stated, the pressure plates 1, 1, 80 are curved longitudinally and are of elastic material so that when the plates are forced into parallelism and maintained straight, they will exert a pressure throughout their length on the tie supported between them 85 and hence smooth out the wrinkles of the tie.

While I preferably employ thin steel plates because of the elasticity and durability of such material, it is, of course, to be 90 understood that I may employ wood, celluloid, fiber, or any other material which is capable of performing the functions stated.

With a device such as above described, ties which are worn during the day can be 95 smoothed out and pressed over night so that they will be fresh and smooth the next day. This will appeal especially to traveling men as the device can be conveniently carried in the grip or handbag, but it is obvious that its 100 use is not limited to travelers, but is also adapted for home use.

Various slight changes might be made in the general form and arrangement of the parts described without departing from the 105 invention, and hence I do not limit myself to the precise details set forth, but consider myself at liberty to make such changes and

alterations as fairly fall within the spirit and scope of the appended claim.

I claim:

5 A tie holder comprising a pair of longitudinally curved pressure plates, a necktie supporting partition plate between the pressure plates, aligned bearing sleeves at one

end of all of said plates, a rod positioned through said sleeves and hingedly connecting the plates together, said pressure plates having aligned tie receiving recesses in their hinged ends, and means for clamping the free ends of all of said plates together.

10 NORMAN M. DYER.
